UNITED STATES PATENT OFFICE.

BENJAMIN H. GIBBS AND CHARLES V. STEWART, OF PHOENIX, ARIZONA.

TRAILER BOAT.

Application filed May 12, 1924. Serial No. 712,668.

To all whom it may concern:

Be it known that we, BENJAMIN H. GIBBS and CHARLES V. STEWART, citizens of the United States, residing at Phoenix, in the county of Maricopa and State of Arizona, have invented certain new and useful Improvements in a Trailer Boat, of which the following is a specification.

This invention relates to improvements in trailer boats readily transportable over land.

An important object of the invention is to provide a boat which may be secured to the rear of an automobile or other vehicles and conveniently transported over the land.

A further object of the invention is the provision of a boat of this character which is collapsible and capable of convenient transportation.

A still further object of the invention is to provide a boat of this character which may be readily collapsed and utilized for carrying numerous articles when operating as a trailer.

A still further object of the invention is to provide a boat of this character which is comparatively simple in construction, yet durable, and efficient for the purpose intended.

Other objects and advantages of this invention will be apparent during the course of the following description.

In the accompanying drawings forming a part of this specification and in which like numerals are employed to designate like parts throughout the same:

Figure 1 is a plan view of the device in folded position,

Figure 2 is a side elevation of the same,

Figure 3 is an enlarged detailed section showing the means for tightly closing the sections,

Figure 4 is a top plan view of the device in open position,

Figure 5 is a vertical sectional view taken on the line 5—5 of Figure 4, and

Figure 6 is an end elevation of the device in collapsed position.

In the drawings, wherein for the purpose of illustration is shown the preferred embodiment of our invention, the numeral 10 generally denotes a boat of the flat bottom type composed of two sections denoted by the numerals 11 and 12. The sections are

somewhat curved to provide more efficient riding ability and enable the boat to travel more easily through the water.

The rear or stern section 11 has an inwardly curved gunwale extension 13 formed about the inner side and adapted to be employed as a rack for supporting the front section 12 when the same is folded over the rear section. The usual seat member 14 is secured transversely in the rear section below the gunwale extension 13. Secured at the extremity of the rear section 11 transversely across the same is a partition or bulk head 15.

The front section 12 is provided with a similar bulk head 16 adapted to be positioned against the bulk head 15 in the open position of the boat. Seat members 17 and 18 are also secured in the front section 12 for the convenience of the occupants. The front and rear sections are hingedly connected by means of a longitudinal hinge 19 extending along the upper edge and connected to the transverse bulk heads 15 and 16, thus enabling the front section to be swung over and positioned upon the rear section. As it is desirable to secure the sections firmly together to prevent movement thereof and retain the boat as a rigid hull the adjoining sides of the sections 11 and 12 have co-acting hasps 20 and 21 secured thereto, the hasps comprising fastening plates 22 and 23 and extension sleeves 24 and 25, the hasps being so constructed as to cause the projecting sleeves upon one to engage the recesses in the other in the open position of the hull, thus enabling the insertion of a longitudinal rod or pin through the aligned openings in the sleeve to securely lock the same in position.

The inner edges of the extension gunwale or rack 13 have concave grooves formed therein, a rubber strip 26 being securely positioned upon the upper side of the grooves to receive the front section. The gunwale of the front section is beveled and carries a rubber strip 27 thus forming a substantially convex surface engaging the concave groove formed in the rear section to form a tight fitting connection when the sections are collapsed or folded.

In order to securely fasten the sections in the folded position to prevent the passage of

water or dirt therethrough, we provide a plurality of fastening devices 28, the type employed comprising a U-shaped swinging bolt pivotally mounted upon the front section and a retaining hasp 30 pivotally mounted upon the rear section and automatically locking the bolt in the downward position. We do not however wish to limit the application of these particular fastening devices, as any suitable locking means may be employed to securely fasten the sections. It is to be noted that the rear extremity or stern plate of the rear section has a V-shaped groove 31 formed therein enabling the stem 15 to fit snugly thereon in the closed position.

In order to permit transportation of the device upon land we provide an axle 32 the central portion being square in cross section as shown and secured transversely across the 20 rear section by means of brackets 33. A pair of wheels are rotatably mounted upon the extremities of the axle 32 and are provided with pneumatic tires 34 upon the rims thereof.

25 In use, the device may be employed to carry baggage or other articles which may be positioned in the rear section, the front section being swung over and positioned on the rear section. The locking devices are 30 then firmly secured and prevent access of dirt, water or other matter within the collapsed structure. The device is then secured to the rear of an automobile or other vehicle and may be readily drawn over the land. 35 When it is desirable to employ the device as a conveyance on water the front section 12 is swung in the open position and the side hasps secured by means of a sliding bolt or rod forming a rigid structure.

40 It is to be understood that the form of our invention herewith shown and described is to be taken as the preferred example of the same, and that various changes as to the shape, size and arrangement of parts may be 45 resorted to without departing from the

spirit of the invention, or the scope of the subjoined claims.

Having thus described our invention, we claim:

1. A combined trailer and boat comprising 50 a boat shaped body composed of a pair of sections, partitions mounted within the extremities of the said sections, hinge means secured to the upper extremities of the partitions to permit folding of the sections, securing means secured to the said sections and retaining same at open position, an extension rack formed in one of the sections to receive the swinging section, strips mounted upon the engaging edges of the sections, means for fastening the sections in the folded position, an axle transversely mounted upon the lower portion of one of the sections, and a pair of wheels rotatably mounted upon the extremities of the said 60 axle.

2. A device of the character described comprising a pair of sections forming a boat in the open position, partitions located at 70 the connecting extremities of the said sections, a hinge mounted upon the upper portions of the partitions to permit swinging of the sections, hasps mounted upon the sides of the sections to rigidly secure the same in the open position, an extension gunwale 75 formed in the rear section, a rubber strip mounted upon the inner edge of the extension gunwale, a V-shaped groove being formed in the stern plate of the rear section, a rubber strip secured upon the gunwale of 80 the front section, fastening devices mounted upon the sections to securely fasten same in the folded position, and a wheel supporting axle secured to the bottom of the rear section. 85

In testimony whereof, we have affixed our signatures.

BENJAMIN H. GIBBS.
CHARLES V. STEWART.
